United States Patent Office

Des. 193,691
Patented Sept. 25, 1962

193,691

PACKAGING CONTAINER

Marshall B. Johnson, Bel Air, Md., assignor to The Black
and Decker Manufacturing Company, Towson, Md., a
corporation of Maryland

Filed July 6, 1961, Ser. No. 65,820

Term of patent 14 years

(Cl. D58—12.6)

FIG. 1

FIG. 2

FIG. 5

FIG. 3

FIG. 6

FIG. 4

FIGURE 1 is a top plan view of a packaging container, embodying my new design;

FIGURE 2 is a front elevational view;

FIGURE 3 is a side elevational view;

FIGURE 4 is a perspective view showing a packaging container, in an open position;

FIGURE 5 is a fragmentary view taken along the lines 5—5 of FIGURE 1; and

FIGURE 6 is a fragmentary rear elevational view thereof.

The broken lines in FIGURE 4 are for illustrative purposes only.

I claim:

The ornamental design for a packaging container, as shown and described.
